UNITED STATES PATENT OFFICE.

HENRY ALBERT OLSSON, OF CINCINNATI, OHIO, ASSIGNOR TO THE BROMWELL BRUSH AND WIRE GOODS COMPANY, OF CINCINNATI, OHIO, A CORPORATION OF OHIO.

AUTOMATIC STOPPING AND LOCKING DEVICE FOR BRUSH-MACHINES.

1,255,921.

Specification of Letters Patent. Patented Feb. 12, 1918.

Application filed September 8, 1914. Serial No. 860,610.

To all whom it may concern:

Be it known that I, HENRY ALBERT OLSSON, a citizen of the United States, and a resident of Cincinnati, in the county of Hamilton 5 and State of Ohio, have invented certain new and useful Improvements in Automatic Stopping and Locking Devices for Brush-Machines, of which the following is a full, clear, and exact description.

10 This invention relates to automatic stopping, and locking devices for brush machines.

The object of the invention is to provide 15 automatic means on brush machines for stopping the drilling and filling tools at a certain predetermined time, and stopping the movement of the work supporting members at a predetermined time, in order to keep all the actuating mechanism in proper 20 timed relation, and in position for the beginning of another cycle of operation.

In brush machines such as illustrated and described in my co-pending application Serial Number 832,659 filed April 17, 1914, it 25 is necessary to provide automatic stopping means for stopping the drilling and filling tools in proper timed relation one with the other and with relation to the operating mechanism, in order to avoid the breaking 30 of either of the tools by the movement of the work supporting members while the drilling and filling tools are engaging same. Furthermore, the different actuating parts 35 of the machine must not travel beyond their proper position after the brush back has been completely bored and filled, owing to the difficulty in bringing the actuating parts of the machine back again to their proper starting position.

40 Another object of this invention is to provide an automatic stop for all the actuating mechanism of the brush machine making it possible to stop the different actuating parts of the machine at any desired point in their 45 cycle of operation.

In the machine to which this device is applied, a reciprocating and rotating master drum is employed which is provided with a series of actuating bars mounted 50 thereon which operate the mechanism for moving the work supporting members by engaging same and pushing said mechanism to one side or the other as desired. In a complete cycle of rotation of said drum one 55 brush back is bored and filled, and if there

are ninety holes in the brush back, ninety actuating bars have been used in the operation, and in order to bring the first actuating bar back to its starting position the drum must continue to rotate after the brush 60 back has been completed, provided there are, say 100 bars on the drum. But, however, the drilling and filling tools must stop in their starting position immediately upon the finishing of the boring and filling of the 65 brush back.

Therefore, it is necessary to provide an automatic stopping device for the machine which will stop the drilling and filling tools at the proper time, but will allow the drum 70 to rotate further a certain distance before stopping, in order to complete its cycle of operation.

My invention consists in certain combinations of parts and details of construction as 75 will be described in the following specification and pointed out in the appended claims.

The brush machine to which this invention is applied employs operating mechanism for the work supporting members and also 80 means for the boring mechanism, said means however, preferably deriving their power from the same source. The operation of the work supporting members is stopped by independent means, coöperating with the driv- 85 ing means of the machine after the boring mechanism has been stopped. This is necessary in order to provide for brush backs of various sizes having more or less holes or tufts. 90

In the drawings:

Figure 1 is a side elevation of a brush machine equipped with my invention.

Fig. 2 is a cross section taken substantially along the line 2—2 of Fig. 1. 95

Fig. 3 is a front elevation of the brush machine parts being broken away for the sake of clearness.

Fig. 4 is a detail view of the lever mechanism for operating the clutches of the device, parts being broken away for the sake of clearness. 100

Fig. 5 is a sectional detail view taken substantially along the line 5—5 of Fig. 2.

Fig. 6 is a cross section taken substantially on the line 6—6 of Fig. 2. 105

Fig. 7 is a detail view of a fragment of the hub of the fly wheel showing the clutch key engaging the recesses in said hub to form a clutch. 110

Fig. 8 is a perspective view of the half round clutch key and pawl attached, employed in my invention.

Fig. 9 is a front elevation of the cam for 5 imparting reciprocating movement to the drilling and filling tools.

Fig. 10 is a plan view partly broken away, showing the mounting of the master drum and driving mechanism.

10 Referring more particularly to the drawings; 1 indicates the base of a brush machine and 2 the legs thereof. The top 4 of the frame constitutes the base upon which the tufting and drilling mechanism operates, while that part of the top indicated at 5 constitutes the base upon which the work supporting members 6 operate.

The work supporting members 6 and their operation are fully explained and illustrated 20 in my aforesaid co-pending application, and it is not deemed necessary to describe them in detail here.

A reciprocating and rotating master drum 7 is mounted on reciprocating bearings or 25 rollers 8 which operate on tracks 9.

Actuating bars 10 are mounted in slots around the periphery of the drum 7 and control the movement of actuating mechanism (shown in a general way at 11) all of which 30 it is not thought necessary to illustrate in this application inasmuch as a full detailed description thereof is found in my aforesaid co-pending application and it forms subject matter for the said application.

35 The mechanism 11 operates the work supporting members in a number of different directions relative to the drilling and filling tools 12. The master drum 7 is mounted on the sleeve 13. The sleeve 13 is mounted on 40 the drive shaft 14 which is driven by the pulley 15 which in turn is driven by a belt or any other suitable means. The shaft 14 has a pulley 17 mounted at the opposite end from that of the pulley 15 and a belt 18 45 connects same with the fly wheel 19 thereby driving said fly wheel.

The fly wheel 19 is mounted on a sleeve 21 near the front of the machine and the sleeve in turn is mounted on the shaft 20 (Fig. 2) 50 said sleeve being mounted in a bearing 22 said bearing being properly mounted on one of the legs 2 of the frame of the machine. The shaft 20 is mounted in a suitable bearing 23 in one of the legs 2 of the frame of 55 the machine at the opposite end from that upon which the fly wheel is mounted.

Mounted tight upon the shaft 20 is a bevel gear 24 which is provided with clutch teeth 25 for engagement with a clutch member 26 60 which is provided with the recesses 27 of the clutch for interlocking with the clutch teeth 25 of the gear 24. The bevel gear 24 meshes with another bevel gear 28 mounted on the shaft 29 supported in bearings 30 extending 65 from the top of the frame of the machine.

Thus, the shaft 29 actuates the boring mechanism by means of mechanism, (not shown) said mechanism forming no part of this invention and being well known in the art, and therefore not considered necessary to 70 illustrate.

The clutch member 26 is provided with an annular channel 31 which pins or rollers 32 mounted on the yoke 33 of the operating rocker arm 34 engage. The clutch member 75 26 is slidably mounted on the hub 35 of the bevel gear 36 but is rotatable therewith (Fig. 2) and said hub is keyed to sleeve 21 by key 37.

The operating rocker arm 34 is loosely 80 pivoted at 38 on the shaft 39 (Fig. 1) and is connected at its upper end with a connecting link 40 which in turn is connected to an arm 41 which is mounted rigidly on the shaft 42 said shaft 42 being mounted in bearings 43 85 mounted on the frame of the machine. At the front end of the shaft 42 I provide a handle 44 for operating the said shaft 42. Thus when the handle 44 is raised it will rock the shaft 42 owing to its being rigidly 90 fastened thereto, said shaft in turn operating the arm 41 also rigidly fastened on the shaft 42, arm 41, operating the link 40 and in turn operating the operating rocker arm 34, thereby throwing the clutch member 26 95 into engagement with the bevel gear clutch member 24. Mounted at the other end of the shaft 42 (Fig. 1) I provide a crank arm 45 extending horizontally therefrom and at the end of which a hanging connecting link 100 46 is mounted, which is connected to a pivoted dog 47, said dog being pivoted on the shaft 48' which is mounted in a suitable manner on the leg 2 of the machine. Thus it is seen that when the handle 44 is raised 105 the dog 47 is also lifted out of engagement with the dial or disk 48 which dial forms a timing device for stopping the machine.

Another dial 49 is provided which has a notch 50 adapted to be engaged by another 110 dog 51 also pivoted on the shaft 48' but connected by connecting rod 52 to a crank arm 53 mounted near the end of the shaft 39 near the bottom of the machine and therefore operated at the same time that the operating 115 rocker arm 34 is operated.

The bevel gear 36 meshes with bevel gear 54 which is rigidly mounted on a shaft 56 said shaft being mounted in suitable bearings 57 on the frame of the machine, and 120 bevel gear 58 mounted at the other end of said shaft 56 meshing with a bevel gear 59 which is mounted on the sleeve 13 which sleeve operates reciprocating and rotating mechanism for the master drum 7. 125

Mounted on the shaft 56 I provide a worm wheel 60 which meshes with the worm wheel 61 tightly mounted on the stud or shaft 62. This worm wheel 61 carries the dials or disks 48 and 49 the former being in this case 130

adjustable circumferentially on the shaft 62 by means of the slot 64 and cap screw 65.

In order to stop the reciprocating movement of the boring mechanism I provide the connecting rod 66 (Fig. 3) which connects the lever operating rocker arm 34 with the slidable extension 67 on the sliding member 68 having an extension 69 which engages the recess 70 in the driving cam 71, which driving cam is mounted on the shaft 20. The sliding member 68 is mounted in the bearing 72 and has a pin 73 extending laterally therefrom and passing through the slots 74 in the bearing 72. Thus when the rocker arm 34 is in the position shown in Fig. 3 the extension 69 is locking the driving cam 71 against rotation.

In order to cause the fly wheel 19 to drive the mechanism of the machine I provide a clutch which will now be described. The fly-wheel is provided with the hub 75 which rotates on a bushing or sleeve 76 which is keyed by means of the key 77 to the sleeve 21 on the shaft 20. This sleeve 76 is provided with a pawl 78 (Figs. 2 and 5) which pawl is rigidly mounted on the key 79, said key being semicircular in cross section as shown in Fig. 8. The key 79 rests normally in a semicircular slot in the sleeve or bushing 76 and is mounted in the lugs 80 on said sleeve 76 as best shown in Figs. 2 and 5. The pawl 78 is provided with a compression spring 81 mounted at the end thereof, said compression spring passing into a recess 82 in the sleeve or bushing 76 and tending to force said pawl to its outermost position shown in dotted lines in Fig. 5. A series of slots 83 are provided in the hub 75 of the fly wheel, each slot being provided with a horizontal steel key or block 84 for engagement with the key 79. Now when the pawl 78 is allowed to reach its dotted line position shown in Fig. 5 the half round key 79 will assume the position shown in Fig. 7 as soon as one of the slots 83 in the hub 75 of the fly wheel has reached the proper position thus causing the fly wheel to drive the bushing 76 and in turn drive all the other mechanism connected therewith.

The pawl 78 is normally held in the position shown in Fig. 5 by the pin 85. This pin 85 is mounted in a bracket 86 (Fig. 3) the bracket being suitably mounted on the frame of the machine and being provided with the slot 87 through which the connection or pin 88 extends from the sliding pin 85. The pin 88 is in turn fastened to an arm 89 which in turn is mounted on a rocker arm 90 and is reciprocated thereby. This rocker arm 90 is rigidly fastened to the shaft 39 as shown in Fig. 1, and is provided with two extending lugs 91 projecting on each side of the operating rocker arm 34 and allowing a considerable amount

of play for the rocker arm 34 to operate there-between. To adjust this amount of play I provide the set screw 93 which may be adjusted to increase or decrease the amount of play as desired. The bracket 86 which carries the pin 85 also carries the pin 94 below the pin 85. This pin is also slidably mounted in the arm 86 and operated by the moving bracket 89 in a similar manner. It is the purpose of this pin to form a stop for the sleeve or bushing 76 which is provided with the flange 95 having the extension 96 for engagement with said pin 94. Thus it is seen that the pin 94 will prevent rotating so far as to allow the pawl 78 to travel past the stopping pin 85.

The operation of the stopping device is as follows:

The fly wheel being driven constantly, is engaged and disengaged by means of the 85 semicircular key 79. When the handle 44 is raised the operating rocker arm 34 is moved inwardly and immediately causes the members of the clutch A to engage each other, the teeth always being in proper relation due to the stopping mechanism for the cam 71 including the pin 69. The shaft 20 begins to rotate immediately upon the engagement of the clutch A, and clutch A also operates the bevel gear 36 which in turn 90 operates the bevel gear 54, thereby operating the shaft 56. The shaft 56, it is readily seen, operates the master drum by means of the bevel gear 58. The worm 60 being mounted on the shaft 56 operates the worm 100 wheel 61 and is properly gaged so as to move the worm wheel 61 one tooth circumferentially while it is making one revolution. Thus the worm wheel 61 is provided with as many teeth as there are slots for the bars 105 10 in the master drum. The disks or dials 48 and 49 are mounted on the worm wheel 61 and rotate therewith, they being first adjusted to bring their cut away portion into engagement with the dogs 47 and 51 at the 110 proper predetermined time. Thus as the worm 60 rotates the disks also rotate; the dogs, of course have been thrown out of engagement by means of lifting the handle 44 to start the machine. As the handle 44 is 115 lifted the operating rocker arm 34 is tilted or rocked so as to throw the clutch A into engagement which at the same time pulls the crank arm 90 which is tightly fastened to the shaft 39 over therewith, which in turn 120 pulls the bracket 86 therewith, thereby pulling the pins 85 and 94 out of engagement with the pawl 78 and the lug and extension 96, thereby allowing the pawl 78 to operate the half round key in order to cause the fly 125 wheel to drive the clutch mechanism. This it is readily seen immediately starts the entire machine.

Now when the master drum has rotated far enough so as to have brought all of the 130

operating bars into operative engagement with the proper mechanism, the pawl 47 will fall to its lowermost position from the cut edge 101 on the dial, thereby rocking the shaft 42 through the agency of the link 46, rocking the crank arm 41 and connecting crank arm 40, pulling the operating arm 34 to the right till it assumes the position shown in Fig. 3, and disengaging the clutch 5 A, thereby stopping the operating of the shaft 20 and bevel gear 24 and 28. However, as the operating rocker arm 34 is thrown toward the right it does not move the arm 90 which is mounted on the shaft 15 39 owing to the fact that the engaging lugs 91 on the crank arm 90 have enough play there-between to allow the operating rocker arm 34 to return without effecting the movement of the crank arm 90.

20 The dials continue to rotate until the worm wheel 61 makes a complete cycle of rotation when the dog 51 will immediately fall into the slot or notch 50 and will throw the crank arm 90 back to its normal position 25 through the agency of the connecting rod 52, the crank arm 53, the shaft 39, as the crank arm 90 is thrown to its normal position, it is readily seen that the bracket 89 forces the pins 85 and 94 to their normal 30 position where they engage the pawl 78 and extension 96 respectively. It will be noted that the pin 85 will force the pawl 78 to the position shown in full lines in Fig. 5, thereby turning the half round key to the 35 position shown in Fig. 6 and allowing the fly wheel to run freely over the hub of the bushing 78.

It is believed that the operation of the device can readily be understood from the 40 foregoing description. Certain modifications of my invention might be made without departing from its spirit and scope and I do not wish to be confined to the exact details shown.

45 What I claim as new and desire to secure by Letters Patent is:

1. A mechanism of the character described comprising a frame, a drive shaft thereon, operating mechanism on said drive shaft and adapted to be operated independently thereof, an operating shaft mounted in said frame, a sleeve on said operating shaft, a fly wheel on said sleeve, a clutch disposed between said sleeve and said fly 50 wheel controlling the operation of said sleeve with said fly wheel, another clutch on said sleeve, controlling the operation of the operating shaft with said sleeve, a beveled gear mounted on said sleeve, a counter-shaft mounted on said frame, a beveled gear at the end of said counter-shaft meshing with said beveled gear on said sleeve, said counter-shaft adapted to drive the driving mechanism on the drive shaft, a worm on 55 said counter-shaft, timing mechanism adapt-

ed to be driven by said worm, said timing mechanism comprising dials, dogs engaging therewith, said dogs connected by a series of levers to the said clutches whereby one clutch may be operated independently of the other and thereby effect the operation of the operating shaft and the operating mechanism on the drive shaft independently of each other and at predetermined times. 75

2. A mechanism of the character described comprising a frame, a drive shaft thereon carrying independently operable mechanism, an operating shaft mounted in said frame and adapted to operate mechanism supported by said frame, a fly wheel on said operating shaft, and a pair of clutches thereon, the combination with a counter-shaft operatively connecting the mechanism mounted on the drive shaft to one of the clutches on the operating shaft, and means whereby said counter-shaft operates timing mechanism for the disengagement of said clutches independently of each other, substantially as described. 80

3. A mechanism of the character described comprising a frame, a drive shaft thereon carrying independently operable mechanism, an operating shaft mounted in said frame and adapted to operate mechanism supported by said frame, a fly wheel on said operating shaft, and a pair of clutches thereon, the combination with a counter-shaft operatively connecting the mechanism mounted on the drive shaft to one of the clutches on the operating shaft, a worm on said counter-shaft, a worm wheel mounted in said frame, dials operable with said worm wheel, a series of levers and dogs interconnecting said dials with said clutches, said dogs engaging the periphery of said dials whereby the position thereof on said dials controls the disengagement of said clutches at predetermined times. 90

4. A mechanism of the character described comprising a frame, a drive shaft thereon carrying independently operable mechanism, an operating shaft mounted in said frame and adapted to operate mechanism supported by said frame, a fly wheel on said operating shaft, a clutch for said fly wheel, another clutch for throwing the operating shaft into operation, a counter-shaft disposed between and operatively connected with the mechanism on the drive shaft and the latter clutch, timing mechanism adapted to be driven by said counter-shaft and interconnected with the said clutches whereby the said clutches may be caused to disengage by said timing mechanism independently of each other and at predetermined times. 110

5. A mechanism of the character described comprising a frame having two separate mechanisms mounted thereon, each adapted 115

to be operated in timed relation with each other and each provided with a drive shaft, the combination with a counter-shaft operatively connecting the two mechanisms, a fly wheel and a pair of clutches supported on one of said shafts, timing mechanism mounted on said frame and operatively connected with said counter-shaft and means

whereby the said clutches are thrown out of engagement independently of each other and at predetermined times by the operation of said timing mechanism.
